UNITED STATES PATENT OFFICE

JOHN N. NELSON, OF PROVIDENCE, RHODE ISLAND, ASSIGNOR TO UNIVERSAL OPTICAL CORPORATION, OF PROVIDENCE, RHODE ISLAND, A CORPORATION OF RHODE ISLAND

DESIGN FOR A BRIDGE MEMBER FOR AN OPHTHALMIC MOUNTING

Application filed May 15, 1928. Serial No. 26,679. Term of patent 14 years.

To all whom it may concern:

Be it known that I, JOHN N. NELSON, a citizen of the United States, residing in the city of Providence, county of Providence, and State of Rhode Island, have invented a new, original, and ornamental Design for a Bridge Member for an Ophthalmic Mounting, of which the following is a specification, reference being had to the accompanying drawing, forming a part thereof.

Fig. 1 is a face view, Fig. 2 is an enlarged face view and Fig. 3 is a cross-sectional view illustrating the shape of a bridge member for an ophthalmic mounting, showing my new design.

I claim:

The ornamental design for a bridge member for an ophthalmic mounting, substantially as shown.

JOHN N. NELSON.
